UNITED STATES PATENT OFFICE.

JOHN TRUNZER, OF PITTSBURG, PENNSYLVANIA.

HEATER FOR FIRE-PLACES, &c.

SPECIFICATION forming part of Letters Patent No. 349,324, dated September 21, 1886.

Application filed February 5, 1886. Serial No. 190,954. (No model.)

To all whom it may concern:

Be it known that I, JOHN TRUNZER, a citizen of the United States, residing at Pittsburgh, in the county of Allegheny and State of Pennsylvania, have invented certain new and useful Improvements in a Combined Fire-Place and Heater; and I do hereby declare the following to be a full, clear, and exact description of the invention, such as will enable others skilled in the art to which it pertains to make and use the same, reference being had to the accompanying drawings, which form a part of this specification.

My invention relates to an improved combined fire-place and heater, the object being to construct a heater in connection with an ordinary fire-place, and utilize the waste heat from the back and sides of the same; and with this end in view my invention consists in certain details of construction and combination of parts, as will be more fully explained hereinafter, and pointed out in the claims.

In the accompanying drawings, Figure 1 is a front elevation of a fire-place having a heater attached thereto comprising my invention. Fig. 2 is a plan view of the same. Fig. 3 is a sectional elevation of my improvement on the line *x x*. Fig. 4 is a sectional view taken through the heater on the line *y y*, with the coil of pipe *g* broken away.

To put my invention into practice, I provide an outside shell or casing, *a*, of suitable size and form of construction, at the rear and sides of which I construct several smoke-passages *b*, communicating with the chimney, and having two entrances, *c*, below the grate. At the front of these smoke-passages *b*, I construct a box, *d*, having a number of horizontal air-flues, *e*, forming a continuous passage from the base to the top. At the base of this continuous air-passage *e*, I introduce an entrance-pipe, *f*, which conducts air from any desired point. At the top and opposite end of the box *d*, I place or conduct an exit-pipe, *g*, which may be coiled, as shown on the drawings at Fig. 2, thus lengthening the passage of the air over the heated surface. To the front of the box, *d*, I place a heavy tile, *h*, which forms the back wall of the fire-place, and on the top of this back wall I place another tile,

i, of suitable shape, after the manner usual in fire-places. At the base of the back wall *h* is placed a perforated or bored plate, *j*, through which the heated products may pass and circulate about the box or heater *d*. The perforations *l* at the base of the tile *i* are used for the same purpose. An ordinary fire-grate is used in front of the tile *h*, and the entire arrangement is built in the chimney, the front of the casing *a* being flush with the outside wall.

The operation is as follows: When a fire is made in the grate, which, in practice, will be arranged in front of the tile *h*, the products of combustion pass into the smoke-flues *b* about the box *d*, and after circulating through these flues pass into the chimney at the upper end of the casing *a*. The heated air, mixed more or less with combustible products, enters the passages *c* below the grate and also the perforations *l* at the base of the inclined tile *i*, and passes into said flues *b*. I thus highly heat the box *d*. The air, from any convenient place, is conducted into one end of the continuous air-passage *e* by means of pipe *f*, and, following the tortuous course indicated by the arrows on Fig. 4, is discharged in a highly-heated state into the pipe *g*, which, being bent back and forward, lengthens the passage on top of the casing *a* and gives the air in its course a longer time to become heated. This pipe *g* may be conducted to a room above through the chimney-flue, or to any other desired point. It will be observed that, by means of the passages *c* and *j* below the grate and the passages *l* above the grate, I conduct portions of the products of combustion mixed with air into the passages *b*, so that when the walls surrounding them become intensely heated the combustion of the products will be rendered complete.

Having thus described my invention, what I claim, and desire to secure by Letters Patent, is—

1. In a fire-place heater, the combination, with the casing *a*, of the air-flue box *d*, arranged and constructed as described and provided with inlet and exit pipes, the smoke-passages *b*, arranged about this box, the passages *c l j*, communicating with the passages *b*

and the tiles *h* *i* in front of the box and forming the back of the fire-place.

2. In a fire-place heater, the air-heating box *d*, constructed as described and communicating with a coil, *g*, on top of the case *a*, in combination with the smoke-passages *b*, surrounding the sides of this box, the passages

cj, and the passages *l*, all arranged and adapted to operate as described and shown.

JOHN TRUNZER.
